CLAIM

The ornamental design for a child-proof cap for an eye drop container, as shown and described.

DESCRIPTION

FIG. 1 is a front view of a child-proof cap for an eye drop container showing my new design;

FIG. 2 is a front view of the design of FIG. 1 shown in a

position of use attached to an exemplary eye drop container; FIG. 3 is an exploded front view thereof, showing the cap comprising the turnable upper component and the base component, detached from an exemplary eye drop container; FIG. 4 is a top view thereof;

FIG. 5 is a bottom view thereof;

FIG. 6 is a right side view thereof;

FIG. 7 is a front perspective view thereof, showing the upper component of the cap is turned at an angle;

FIG. 8 is a front view thereof, showing the upper component of the cap is turned at an angle;

FIG. 9 is a right side view thereof, showing the upper component of the cap is turned at an angle;

FIG. 10 is a top view thereof, showing the upper component of the cap is turned at an angle; and,

FIG. 11 is a bottom view thereof, showing the upper component of the cap is turned at an angle.

The broken lines shown in FIGS. 1-11 illustrate portions of the child-proof cap for an eye drop container that form no part of the claimed design. The broken lines shown in FIGS. 2 and 3 that illustrate the eye drop container illustrate environment and form no part of the claimed design. The dash-dot-dash lines directly adjacent to the claimed areas shown in FIGS. 1-4 and 6-10 illustrate a boundary and form no part of the claimed design.
